UNITED STATES PATENT OFFICE.

GEORGE E. TITCOMB, OF PHILADELPHIA, PENNSYLVANIA, ASSIGNOR TO
THE DODGE COAL STORAGE COMPANY, OF NAUGATUCK, CONNECTICUT,
A CORPORATION OF CONNECTICUT.

LOCOMOTIVE-CRANE.

No. 853,842.

Specification of Letters Patent.

Patented May 14, 1907.

Application filed January 10, 1906. Serial No. 295,489.

To all whom it may concern:

Be it known that I, GEORGE E. TITCOMB, a citizen of the United States, residing in Philadelphia, Pennsylvania, have invented certain improvements in Locomotive-Cranes, of which the following is a specification.

My invention relates to certain improvements in cranes, and more particularly to certain improvements in the detail construction and arrangement of parts of an electrically operated locomotive crane.

One object of the invention is to provide a crane of this type with such apparatus and such an arrangement of controlling devices therefor, that a single operator may be able to conveniently and efficiently govern the operation of said apparatus with a minimum of physical exertion while being himself in the best position for observing the results of such operation.

A further object of the invention is to provide a simple and reliable device for conducting the electric current for operating the various motors of the crane from the current supply mains to the different controlling devices. I also desire to provide a compact and efficient arrangement of the operating mechanism of a locomotive crane, which shall be of such a nature as to be reliable in operation and so placed as to be conveniently inspected.

These objects I attain as hereinafter set forth, reference being had to the accompanying drawings, in which:

Figure 1, is a vertical section of my invention illustrating in side elevation certain of the operating mechanism and the controlling devices thereof; Fig. 2, is a plan of the crane shown in Fig. 1, further illustrating the arrangement of the apparatus thereof; Fig. 3, is a front elevation of my improved crane; Fig. 4, is a plan view of the truck of the crane; Fig. 5, is a plan illustrating the arrangement of the foot levers for respectively operating the swing motor brake and the master controller of the swing and hoisting motors; Fig. 6, is a vertical section illustrating the preferred arrangement of the levers and shafts for operating the master controller for the swing and hoisting motors; Fig. 7, is a vertical section illustrating the preferred construction of the contact shoe-supporting struc-

ture, and Fig. 8, is an elevation illustrating certain features of the clutch mechanism.

In the above drawings, A represents the framework of the crane truck which is composed of relatively heavy structural sections provided with bearings for the reception of a pair of axles a equipped with wheels a' and preferably so proportioned as to operate on a standard gage track.

Suitably hung from the truck frame A is an electric motor B, whose armature shaft is geared to an intermediate shaft having bevel gears b respectively meshing with bevel gear 65 wheels a² suitably fixed to the axles a. On the truck frame A is a substantially circular track a³, concentric with and inside of which is an annular beveled rack a⁴. At the center of said rack and track is a tubular structure a⁵ fixed to the truck frame and serving as a guiding bearing for the pivot or pintle d of the crane structure proper, which consists of a framework D to whose underside is fixed a circular track d' curved to the same radius as 75 that of the track a³ and concentric therewith. Between the said two tracks d' and a³ is a series of wheels or rollers d² suitably spaced and retained in position by means of a pair of circular rings d⁴ and d⁵.

Suitably mounted upon the frame D, and in the present instance, near one end thereof, is an electric motor E, hereafter referred to as the swing motor, which is connected through gearing to a shaft e provided with a beveled pinion e', so placed as to mesh with the rack a⁴. Connected with the above mentioned gearing is a friction drum e² upon which a brake band e³ is operated, and this is connected through suitable mechanism to a shaft e⁴ having fixed to it a foot lever e⁵ whereby said brake band may be operated to retard or prevent movement of the shaft e after current has been cut off from the motor E.

Pivotedly mounted in the well known manner upon the front of the frame D is the crane boom F and for the purpose of operating the hoisting or lifting device suspended from the end of this boom and also for raising and lowering the boom itself, a third motor G 100 is provided, which is carried by the rear portion of the frame D. The armature shaft of this motor is geared to a shaft g upon which are loosely carried a plain pinion g' and a bev-

eled pinion g^3 . By means of a clutch g^3 this shaft may be made to drive the pinion g' , which meshes with a gear h fixed to the hoisting shaft h' , and there are upon this latter shaft a hoisting drum H and a holding drum H' —the first of these may be operatively connected to said shaft by means of a clutch h^2 , while the latter may be similarly connected by means of a clutch h^3 .

10 Automatic holding or brake mechanism, indicated at h^4 , is provided for the shaft carrying the two drums; being so designed as to prevent them overhauling under the action of a load when current is cut off from the motor G . Since, however, this mechanism is well known to the art and does not form a part of the present invention, it has not been shown in detail.

15 The bevel pinion g^2 , which is loose on the shaft g , meshes with a similar pinion i and it may be operatively connected to said shaft by the clutch g^{10} as shown in Fig. 8. This clutch is operated by the same mechanism as that governing the clutch g^3 , being so arranged that when an operating lever g^6 is in its mid position both clutches are released, while movement of said lever to one side operates one clutch and its movement to the opposite side operates the other. The shaft 20 I extends upward at an angle toward a horizontally placed shaft J carried on the upper portion of the crane framework by means of suitable standards forming an auxiliary framework D' . Said shaft J has fixed to it a worm wheel j engaged by a worm i' on the shaft I , and also has a drum j' for the reception of the ropes whereby the boom is raised or lowered.

25 In order to operate the clutch h^3 of the holding drum H' , I provide suitable actuating means operated from a shaft h^6 , which is controlled by a hand lever h^7 suitably placed at the front of the crane, while the clutch h^2 of the hoisting drum is similarly actuated from a shaft h^8 operated by a lever h^9 , also placed so as to be conveniently manipulated by an operator at the front of the machine.

30 The clutches g^3 and g^{10} , for respectively connecting the drum operating and boom hoisting mechanism with the motor G , are connected through suitable links with the shaft g^6 , to which is fixed the operating lever g^6 ; it being noted that this lever, as well as the levers h^7 and h^9 are all arranged near the front of the crane so as to be conveniently operated by one man.

35 For the purpose of governing the operation of the motors E and G , I provide a single operating device constructed as shown in Figs. 1, 5 and 6, and consisting of a suitable supporting shaft or spindle K to which is keyed or otherwise fixed an arm k having pivotally hung at its end a foot piece k^3 , there being also keyed or fixed to this spindle a sec-

ond arm k^5 connected to a bar k^6 attached to the handle of the master controller e^6 , whereby operation of the swing motor E is governed. The spindle or shaft K also loosely carries a sleeve k^7 to which are fixed two arms k^8 and k^9 ; the former being connected by a link k^4 with the foot piece k^3 and the latter being connected to a bar k^2 attached to the master controller g^7 , whereby the operation of the motor G is governed.

40 In order to return the shaft K and its attached parts to a position corresponding to the "off" position of the two master controllers e^6 and g^7 , I provide a pair of springs (not shown) contained in cylinders l and l' and operative upon rods l^2 connected to an arm k^{10} on said shaft K , said springs being so adjusted that they tend to turn the shaft to its "off" position whenever it is moved therefrom as by the operation of the foot piece k^3 .

45 The motor B is governed by means of any suitable form of controller, the handle of which is shown at b^2 and I provide connections from the field and armature of said motor to suitable contact fingers m' in engagement with the annular segments m of a contact device M supported on the frame D in the line of the pivot d thereof. This pivot structure, as well as the device M , is made hollow for the passage of the conductors to the motor B and also for the main supply conductors for the motors E and G and their controlling apparatus. In order to supply current to these main conductors while the crane is under operation, I provide along the track N on which the crane operates a series 50 of posts P , on each of which is carried a pair of metallic contacts p and p' placed vertically over one another and respectively connected to the positive and negative current supply mains.

55 For the purpose of conducting current from the contacts to the moving crane structure, I provide either one or two collecting devices, (depending on whether the contacts are placed along one or both sides of the track) each of which preferably consists of a pair of shoes formed of angle sections p^2 and p^3 insulated from each other as shown in Fig. 7, and carried upon a pair of links p^4 in such manner that while free to move toward and 60 from the crane structure in the horizontal planes respectively intersecting the contacts p and p' , they are always moved parallel to themselves. In order that the contact shoes may be free to automatically adjust themselves to the various pairs of contacts p and p' , I provide a ball and socket connection between the end of each link p^4 and the vertical bar p^{10} upon which the shoes p^2 and p^3 are carried. A spring contained in a cylinder p^5 65 acts upon the rods p^6 and p^7 connected to arms attached to the links p^4 in such manner as to always tend to swing said links out-

wardly, thereby always tending to yieldingly press the angle pieces or shoes p^2 and p^3 against their respective contacts.

The posts P are so spaced and the shoes p^2 and p^3 are of such length that the latter are always in engagement with at least one set of contacts p and p' ; the ends of said shoes being curved inwardly so as to properly engage the various contacts as the crane is moved.

10 Under working conditions, a single operator standing at the front of the crane and adjacent to the foot of the boom, is enabled to intelligently and conveniently govern the operation of the entire apparatus, since he is not only in position to see the material being handled and the work done by a bucket or hoisting device carried by the boom, but can also, without leaving his position, manipulate with but little physical exertion, all of 15 the necessary levers for controlling the different parts of the apparatus. For example, if it be desired to move the crane as a whole upon its tracks N, the controller handle b^2 is turned to the right or left, thereby supplying 20 current to the motor B to cause it to operate in one direction or the other, to bodily propel the crane structure.

If it is desired to operate the motor G, so as to cause it to hoist material suspended from 30 the end of the boom F, the foot piece k^3 is pressed downwardly by the right foot of the operator, thereby actuating the master controller g^7 , which in turn supplies current to well known forms of automatic switches 35 (not shown) so that said motor is started and speeded up under predetermined conditions and in a predetermined time, while either one or both of the drums H and H' may be caused to operate by throwing the lever g^8 in one direction and properly manipulating either one or both of the levers h^7 and h^9 . If it be desired to raise the boom F, this may be done by throwing the lever g^8 in a direction opposite to that above noted, thereby operating 45 the clutch g^{10} , while leaving the clutch g^9 in its released position.

In order to swing the upper portion of the crane structure, that is, the frame D with the parts supported thereon, the foot piece k^3 is 50 pushed forwardly or to the rear. In the former case such action turns the arm k^3 on shaft K, and thereby moves the handle of the master controller e^6 so as to supply current to the motor E and cause it to swing the crane 55 with the boom to the right, while if said foot piece be moved to the rear, the master controller e^6 is so operated that the direction of rotation of the motor E is reversed and the crane is swung to the left.

60 It is obvious that, if desired, the foot piece k^3 may be moved to the front or rear and at the same time pressed downwardly, with the result that the boom is swung to the right or left and simultaneously the bucket or other 65 hoisting device carried by it is elevated. If

it is desired to stop the rotation of the crane structure on its pivot, this may be done by pressing down on the lever e^6 , thereby applying the brake e^7 to the shaft e and preventing or retarding further rotation of the beveled pinion e^8 .

The two sets of the contact devices are not necessarily employed, since if the crane track N be straight throughout its extent, one set of such contacts devices and a single series of 75 the contact posts P may be all that is required. If, however, there are curves on the crane track N, it may be advisable to employ current collecting devices and contact posts on both sides of the crane.

80 As will be understood by those skilled in the art, a number of banks or bodies of resistance are required for the control of the current flow to the various motors and these are preferably mounted in the space x' , Fig. 85 1, at the rear of the crane structure. Similarly the automatic resistance controlling switches are mounted in the space x though both these as well as the resistance have been omitted from the drawings to avoid complications thereof.

One important advantage possessed by the combination of my improved crane with the contact carrying standards for supplying its electric apparatus with current is due to the 95 fact that while said standards support their contacts at such a height as to avoid the possibility of ice, snow or water interfering with their functions, there is no liability of accidental short circuits from misplaced metallic pieces or interference with the free operation 100 of the crane, and in addition clear spaces are left between said standards which permit the free passage of wagons or trucks to all parts of the stock yard in which the crane is customarily installed.

I claim:

1. The combination in a crane of a supporting frame, a structure pivotally mounted thereon and provided with a boom, means for swinging said structure on its pivot, hoisting means, and means for controlling said hoisting and swinging means, the same including an operating device common to both of 110 said controlling means, substantially as described.

2. The combination of a supporting frame, a structure pivotally mounted thereon and provided with a boom, hoisting mechanism, a motor for swinging said structure on its pivot, a second motor for operating said hoisting mechanism, a controller for each of 115 said motors, and an operating member common to both of said controllers, substantially as described.

3. The combination of a supporting frame, a structure pivotally mounted thereon and provided with a boom, hoisting mechanism, a motor for swinging said structure on its pivot, a second motor for operating said 120 125 130

4
hoisting mechanism, a controller for each of said motors, and an operating member common to both of said controllers, said member being supported so as to be movable in a plurality of lines, and having connections to the controllers so arranged that its movement in one line operates one controller, while its movement in either of two other lines actuates the second controller, substantially as described.

5. The combination of a supporting frame, a structure pivotally mounted thereon and provided with a boom, hoisting mechanism, a motor for swinging said structure on its pivot, a second motor for operating said hoisting mechanism, a controller for each of said motors, and an operating member com-

mon to both of said controllers, said member being supported so as to be movable in a plurality of lines and having connections to the controllers so arranged that its movement in one line operates one controller, while its movement in either of two other lines actuates the second controller, the controllers being connected to be simultaneously operated by movement of said member in another line or lines, substantially as described. 20 25

In testimony whereof, I have signed my name to this specification, in the presence of two subscribing witnesses.

GEORGE E. TITCOMB.

Witnesses:

WILL A. BARR,
Jos. H. KLEIN.
